GROMMET

Francis E. McGee, Baltimore, Md.

Application March 9, 1942, Serial No. 433,932

1 Claim. (Cl. 102—1)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to a protector for the rifling band of projectiles, or what is known in the art as a grommet. The device is closely allied to protectors used for pipe threads and may be used for that purpose.

A desirable grommet should possess the qualities of easy application combined with the security of attachment and ease of removal. Furthermore, in times of vast production it becomes increasingly desirable to utilize an article which is simple of manufacture and economical of essential raw materials. With respect to the security of attachments, the loading and shipping of projectiles subjects them necessarily to a great deal of abuse, this being of small consequence to the shell proper, but often proving fatal to the soft and precisely dimensioned rifling rings. The known grommets have not proved equal to such hazards because of a tendency to compromise with ease of application and removal. With respect to the latter, it is essential that gunners in the field be able to remove the grommets in any and all conditions of illumination or weather and often to do so without removing their gloves.

Another drawback of known grommets is the space they require for shipment from the factory. This is obviated in the present invention by making the grommets in separable parts whereby they may be nested. These parts are assembled into a hinged grommet which is easily placed about the rifling rings.

It is therefore an object of the invention to provide a grommet of sturdy construction, fabricated of inexpensive, plentiful materials, which shall be easy to ship, assemble and apply, certain of protection when applied and easy to remove at will.

To these and other ends, the invention consists in the construction, arrangement and combination of elements described hereinafter and pointed out in the claim forming a part of this specification.

A practical embodiment of the invention is illustrated in the accompanying drawing wherein:

Figure 1 is a top plan view of a preferred embodiment.

Figure 2 is a fragmentary view in elevation showing the hinge of Fig. 1.

Figure 3 is a fragmentary view in elevation showing the fastener of Figure 1.

Figure 4 is a section taken on the line 4—4 of Figure 1.

Figures 5 and 6 are views similar to Figure 3 showing modifications.

Figures 7 and 8 are views similar to Figure 2 showing modifications.

Figure 9 is a top plan view of the hinge of Figure 8.

Figure 10 is a broken elevational view of a half section of a modified grommet, and

Figure 11 is a broken top plan view showing the join of two such members as in Figure 9, and

Figure 12 is a fragmentary view showing a modification of the fastener of Figure 3.

Referring to the drawing by characters of reference there is shown a grommet having outer semicircular bands 1 of sheet steel or any durable metal or other material having inturned flanges 2 forming an inner circumferential channel. Received in the channel between flanges 2 and secured as by rivets 3 or any other suitable means 20 are resilient members 4 which may be cotton webbing, rubber, pressed paper, lignon or any other suitable material, the list here given not being intended to be exhaustive since the only requirement is that the material present a comparatively soft layer at the rifling rings and the selection of material need only be guided by the exigencies of availability, cost and ease of fabrication. The same is true of the material forming 30 the outer shield 1.

It has been found that the desiderata of ease of application and removal, together with economy of space in shipment are confluent in a grommet having hinged sections, since they may be slipped on or off the projectile without straining against a natural and considerable arcuate resiliency and may be nested for shipping whether already hinged or separate.

The hinge shown in the preferred form comprises a U-shaped pin 5 engaging in loops 6 40 formed by turning back the ends of shield 1.

For the fastening means, arched portions 7 are struck outward at the termini of the shields 1 opposite the hinge portions. The arches 7 are struck in line with a previously formed perforation 8 which may be made by punching, and which serves as a passage for a threading means such as the wire 9. The arch 7 has its rear slope intersecting the span of the perforation 8 whereby the latter is raised on a slant from the 50 surface of shield 1 to facilitate easy threading.

For fastening the grommets, a wire is simply inserted through the arches 7 and twisted in any convenient manner for retention therein. Any other known form of securing means may be used instead of the wire, such as a cotter pin or spring clip.

A better distribution of the clamping force may be attained by provision of additional arches 1 as shown in Figures 5 and 6. In this case the arches are shown as merely struck, without the perforations 8 added.

Securement against lateral displacement while on the rifling band is provided for by flanges 9a at the sides of the resilient member which overlap the extremities of the rifling band and by intermediate rib 10 designed to fit into a gas check groove in the band, it being understood that the pattern may be varied to suit any particular rifling band.

A simply constructed type of grommet of easy application is shown in Figures 10 and 11. A band 11 is formed with a tongue 12 and a slot 13 nearby, and a slot 14 at the opposite end slightly raised to form bridges 15 and 16 constituting receiving means for a tongue such as 12. The bridge 16 may be entirely struck from the band 11 to leave a slot. A grommet may be formed of a single such band 11 or of any desired number, since they may be attached, chain fashion. The band 11 in the case of a grommet of a single unit is wrapped around the projectile, passed through the slots 14 at the other extremity of the band, wrapped back on itself and secured in slots 13. The single band type does not have the advantages of the hinged type but if two or more units are attached by means of a tongue fastened through the slots 14 on the next succeeding unit, the tongue joint will serve

as a hinge. The units 11 may be made very short and used in proper multiples to fit various sizes of shells. This will solve a production problem having to do with the number of types necessary to provide for in fabricating, storing, shipping and issuing. In the case of a short unit 11, in addition, the curvature may be dispensed with, since small tangent members will approximate a true circumference and also by this means adjustment is possible to bring an integral number of units into engagement with any projectile regardless of size.

A simple hinge such as shown in Figure 3 with a short tongue 17 passed through a slot 18 in the adjacent band may be employed in any hinged type described herein. The advantage of this type as well as that of Figure 2 is that it is capable of repeated flexing without fatigue. However, since repeated flexing will seldom be encountered, the simpler types such as that of Figure 7 will in general suffice.

In order to smooth the circumferential profile of the protector as an aid in shipping and to do away with annoyance, delay and injury to 25 the users, the regions having the fastening means and hinges may be located in a depression in the armor 1 as shown in Figure 12.

I claim:

30 A component for rifling bands of projectiles comprising a strip, a tongue on one end of said strip, a pair of parallel slits crosswise of the strip, one near the tongue and of a length to receive the width of the tongue and a similar 35 slit in the end of the strip opposite the tongue carrying end, the tongue attached to the slit remote from the tongue and bent back and passed through the adjacent slit in its own strip.
